UNITED STATES PATENT OFFICE.

LOUIS J. CARTIER, OF BUDAPEST, HUNGARY, ASSIGNOR TO CARTIER, SOCIÉTÉ ANONYME, OF PARIS, FRANCE.

FASTENING DEVICE FOR WATCHES AND OTHER ARTICLES OF JEWELRY.

Application filed July 6, 1927, Serial No. 203,845, and in France October 21, 1926.

My invention relates to improvements in a device for pinning articles of adornment to the clothing and the objects of the invention are, first, to provide a device of the character indicated in which the pin tongues are rotatable in a plane parallel to the article upon which the device is attached, second, to provide means for releasably locking the said pin tongues at each 90° displacement thereof, and, third, to provide additional means for locking said pin tongues at their extremities when moved to closing position after having been inserted through the material upon which the device is to be attached.

Other objects of the invention will be obvious to those skilled in the art to which the invention relates with reference to the following description when taken in connection with the accompanying drawing forming 20 part of this specification and in which—

Fig. 1 is a plan view of a watch upon which the device is mounted;

Fig. 2 is a front elevational view of Fig. 1 showing my improved fastening means;

Fig. 3 is a rear view of Fig. 1;

Fig. 4 is a view similar to Fig. 3 showing the device in another position;

Fig. 5 is a section taken along the line 5—5 of Fig. 3;

Fig. 6 is a section taken along the line 6—6 of Fig. 5;

Fig. 7 is a rear view of my device provided with a modified form of fastening means;

Fig. 8 is a front elevational view of Fig. 7;

Fig. 9 is a plan view of my device applied to an article of adornment showing a modified form of fastening means;

Fig. 10 is a section on the line 10—10 of Fig. 9;

Fig. 11 is a section on the line 11—11 of Fig. 10; and

Fig. 12 is a view looking from beneath in Fig. 9.

Referring to the drawing and more particularly to Figs. 1 to 6, a pair of pin tongues 1 is rigidly secured to a plate 2 by soldering or other suitable expedient. The plate 2 is loosely mounted on a stud screw 3 which extends clear through one end of the watch casting 3' and which is adapted to screw into the opposite wall of the said watch case 3'. The outer extremities of the said pin tongues 1 are adapted to be lodged in a groove 4 provided on the watch case 3'.

I preferably provide the shaft 3 with a

square sleeve loosely mounted thereon and fixed to the plate 2 as shown at 5 in Figs. 5 and 6. Surrounding the said sleeve is preferably an elongated slot 6' in which are disposed U-shaped springs 6 and 7 having inverted curved extremities. The slot 6' is adapted to be closed by means of a plate 8 acting as bearing for the plate 2 and which is secured in position by means of screws 9 entering internally threaded collars 9a fixed in the bottom 8' of the said slot.

The pin tongues 1 are adapted to bear against the top of the groove 4 with sufficient friction to hold them in the desired position. In some cases however, I may prefer to close one end of the groove 4 as shown at 8' (Figs. 7 and 8) and provide the other end of the said groove with a spring catch 9' for closing the said other end.

From the foregoing it will be obvious that when it is desired to attach the watch to the clothing the pin tongues are moved to the position shown in Fig. 4 and inserted through the clothing with their points slightly projecting. The watch is then turned in either direction until the pin tongues enter the groove 4, and are held there either by friction or by the catch 9'. It will be noticed that during the turning operation the square sleeve 5 which is fast to plate 2 is also turned. When the corners of said sleeve slide over the springs 6 and 7 the turning movement is retarded, that is, opposition is offered thereto. The turning movement takes place in two 90° steps which greatly facilitates attaching of the device to the clothing which may readily take place with only one hand if necessary. Once the pin tongues are in closing position in the groove 4, the springs 6 and 7 engaging the flat sides of sleeve 5 are sufficient to hold the said tongues from any ordinary displacing force and with the arrangement shown in Figs. 7 and 8 displacement becomes practically impossible.

The device as before stated is adaptable to any articles of adornment conformable thereto. In Figs. 10 to 12 the device is shown as applied to a brooch in combination with a specific form of catch for the groove which retains the pin tongues in closed position. As therein shown, a brooch 1^b is provided at one end with a hollow collar 3^b on which is supported in precisely the same manner as previously described a plate 2^b by means of a stud screw 3^c. The said plate is provided

with the usual pin tongues 1 and the sleeve and spring arrangement is disposed within the collar 3^b in precisely the same way as previously described with the exception that the 5 plate 8 in this embodiment is sunk within the collar 3^b so as to lie flush with the top thereof and therefore does not appear on these figures.

The other end of the brooch is provided 10 with an upstanding block 10^b provided with the usual groove 4^b closed at one end as shown at 8^b. Longitudinally of the groove is mounted a leaf spring 10 secured at one end by means of rivets 11 adjacent the closed end 15 of said groove and carrying at the opposite end with a catch 9^b, adapted to close the open end of groove 4^b. The said catch is provided with a sloping face against which the pin tongues come in contact when entering the 20 groove 4^b. The spring 10 is moved to a position to uncover the end of groove 4^b by means of a lug 12 having a milled surface disposed thereon at right angles and extending through a slot in member 10^b.

25 While I have shown and described what I deem to be the preferable forms of my device I do not wish to be limited thereto as there might be various changes made in the details of construction and the arrangement of the 30 parts without departing from the spirit of the invention comprehended within the scope of the appended claims.

Having thus described my invention what I claim as new and desire to secure by Letters 35 Patent is:

1. In a device of the type described having a plurality of pin tongues, pivotally mounted means supporting said tongues and adapted to permit said tongues to be rotated in a plane 40 parallel to the surface of the object upon which said device is to be attached and a grooved element for receiving the extremities of said tongues.

2. In a device of the type described having 45 a plurality of pin tongues, pivotally mounted means supporting said tongues and adapted to permit said tongues to be rotated in a plane parallel to the surface of the object upon which said device is to be attached, a grooved element for receiving the extremities 50 of said tongues and means for releasably confining said tongues in said groove.

3. In a device of the type described having 55 a plurality of pin tongues, pivotally mounted means supporting said tongues and adapted to permit said tongues to be rotated in a plane parallel to the surface of the object upon which said device is to be attached including a fixed stud screw and a plate loosely mounted 60 on said stud screw carrying said tongues and a grooved element for receiving the extremities of said tongues.

4. In a device of the type described having 65 a plurality of pin tongues, a pivotally mounted plate carrying said tongues and adapted

to permit said tongues to be rotated in a plane parallel to the surface of the object upon which said device is to be attached, a grooved element for receiving the extremities of said tongues, means for releasably confining 70 said tongues in said groove and resilient means tending to oppose rotation of said plate at each quarter revolution thereof.

5. In a device of the type described having a plurality of pin tongues, a pivotally mounted 75 plate carrying said tongues and adapted to permit said tongues to be rotated in a plane parallel to the surface of the object upon which said device is to be attached, a grooved element for receiving the extremities 80 of said tongues and resilient means tending to oppose rotation of said plate at each quarter revolution thereof.

6. In a device of the type described having 85 a plurality of pin tongues, pivotally mounted means supporting said tongues and adapted to permit said tongues to be rotated in a plane parallel to the surface of the object upon which said device is to be attached, a grooved element for receiving the extremities 90 of said tongues, a fixed stop at one end of said groove and a releasable stop catch at the other end of said groove for confining said tongues in said groove.

7. In a device of the type described having 95 a plurality of pin tongues, a pivotally mounted plate carrying said tongues and adapted to permit said tongues to be rotated in a plane parallel to the surface of the object upon which said device is to be attached, a grooved 100 element for receiving the extremities of said tongues, a fixed stop at one end of said groove, at releasable stop catch at the other end of said groove for confining said tongues in said groove and resilient means tending to 105 oppose rotation of said plate at each quarter revolution thereof.

8. In a device of the type described having 110 a plurality of pin tongues, pivotally mounted means supporting said tongues and adapted to permit said tongues to be rotated in a plane parallel to the surface of the object upon which said device is to be attached, a grooved element for receiving the extremities of said 115 tongues, a fixed stop at one end of said groove, a leaf spring disposed in said groove having one end fixed at a point adjacent said stop, a catch lug disposed on the other end of said 120 spring and adapted to normally close the open end of said groove, a slot formed in said grooved member at right angles to said groove and an operating lug carried by said spring and projecting through said slot.

9. In a device of the type described having 125 a plurality of pin tongues, pivotally mounted means supporting said tongues and adapted to permit said tongues to be rotated in a plane parallel to the surface of the object upon which said device is to be attached including a fixed stud screw and a plate loosely 130

mounted on said stud screw carrying said tongues, a hollow supporting element for said screw and said plate, a sleeve carried by said plate extending into said supporting element and springs in said supporting element associated with said sleeve and adapted to oppose rotation of said sleeve at every quarter revolution of said plate.

10. In a device of the type described having a plurality of pin tongues, pivotally mounted means supporting said tongues and adapted to permit said tongues to be rotated in a plane parallel to the surface of the object upon which said device is to be attached in-

cluding a fixed stud screw and a plate loosely mounted on said stud screw carrying said tongues, a hollow supporting element for said screw and plate, a square sleeve fixed to said plate and extending into said supporting element and a substantially U-shaped spring disposed on each side of said sleeve, said springs each having a flat portion disposed against the flat side of said sleeve and in-turned curved extremities for the purpose disclosed.

In testimony whereof I have signed this specification.

LOUIS J. CARTIER.
